Primary Examiner — Joseph Kukella*Assistant Examiner* — Darryl J Dardenne(74) *Attorney, Agent, or Firm* — LADAS & PARRY LLP(57) **CLAIM**

The ornamental design for a squeezing machine, as shown and described.

DESCRIPTION

FIG. 1 is a front elevation view of a squeezing machine showing our new design;

FIG. 2 is a left side elevation view, thereof, the right side elevation view being a mirror image thereof;

FIG. 3 is a top plan view thereof; and,

FIG. 4 is a perspective view thereof.

The squeezing machine is intended to squeeze fruit in order to obtain fruit juice.
